meinhard Witte

UNITED STATES PATENT OFFICE.

MEINHARD WITTE, OF MINNEAPOLIS, MINNESOTA.

RADIATOR-CORE-ASSEMBLING MACHINE.

Application filed April 24, 1922. Serial No. 556,285.

To all whom it may concern:

Be it known that I, MEINHARD WITTE, a citizen of the United States, residing at Minneapolis, in the county of Hennepin and State of Minnesota, have invented certain new and useful Improvements in Radiator-Core-Assembling Machines; and I do hereby declare the following to be a full, clear, and exact description of the invention, such as will enable others skilled in the art to which it appertains to make and use the same.

My invention provides an extremely simple and highly efficient machine or apparatus for rapidly assembling the tubes and radiating fins that make up the cores of radiators, such as used in connection with automobiles. Particularly, the machine is designed for the assembling of triangular tubes and thin sheet metal radiating fins of the character disclosed and claimed in my pending application Serial Number 416,083, filed October 11, 1920, and entitled "Radiators".

Broadly stated, the present invention comprises a plurality of parallel tube-spacing plungers and an assembling box or frame for properly spacing the radiating fins and holding the same while the tubes are simultaneously moved through the aligned tube passages of the assembled or properly spaced radiating fins.

The preferred form of the machine is illustrated in the accompanying drawings, wherein like characters indicate like parts throughout the several views.

Referring to the drawings:

Fig. 1 is a side elevation of the complete assembling machine, some parts being sectioned;

Fig. 2 is a plan view thereof, some parts being broken away;

Fig. 3 is a transverse vertical section taken on the line 3—3 of Fig. 1, looking toward the right in respect to Fig. 1;

Fig. 4 is a section on the same line as Fig. 3 but looking toward the left in respect to Fig. 1;

Fig. 5 is a fragmentary perspective showing a group of tube-spacing plungers with portions of the tubes thereon;

Fig. 6 is a fragmentary perspective showing a portion of the so-called fin-assembling box;

Fig. 7 is a fragmentary plan showing a

portion of the lower plate or member of the assembling box;

Fig. 8 is a bottom plan view showing a portion of the upper plate or section of the assembling box; and

Fig. 9 is a perspective showing a portion of one of the radiating fins.

The several parts of the assembling machine are mounted directly or indirectly on a flat skeleton bed frame shown as made up of parallel I-beams and suitable cross-connected beams.

Suitably anchored on the rear or right-hand portion of the frame 10 is a cylinder 11 in which works a piston 12, the front end of which latter works through adjacent cylinder head ends connected to a cross-head 13, which cross-head is slidable on guide rods 14 rigidly secured to brackets 15 on the frame 10. A suitable motive fluid, preferably air, is alternately delivered into opposite ends of the cylinder 11 from a sort of a supply pipe 16 having branches 17 that lead to the opposite ends of said cylinder. The numeral 18 indicates a three-way valve applied at the junction of the pipes 16 and 17, and by manipulation of which the opposite ends of the cylinder, in alternate order, may be connected to the atmosphere and to the compressed air supply, so that by manipulation of said valve, reciprocating movement of the piston and, hence, of the cross-head 13 can be produced, at will.

The cross-head 13 carries a transverse bar 19 provided at its ends with lugs 20 in which trunnions on the ends of a rocker bar 21 are journaled.

The tube-spacing plungers 22 for the spacing of tubes, such as employed in the radiator of my prior application, are triangular in cross-section, are spaced to correspond to the proper spacing of the tubes in the radiator core, and at their rear ends are rigidly secured to the rocker bar 21. Said plungers 22 are preferably provided with reduced ends to adapt them to be detachably secured in perforations 23 formed in the rocker bar 21, (see Fig. 3, in which view certain of the plungers at the end are omitted to provide the proper number of plungers for the particular radiator core illustrated herein).

The triangular tubes, which form the water tubes of the radiator core, are indi-

cated by the character *a* and the radiator fins are indicated by the character *b*. These fins *b*, which are preferably of sheet brass or copper, are, as illustrated, of the character disclosed and claimed in my prior pending application above identified and they are corrugated, provided with over-turned edges *b*¹ and are formed with triangular tube passages *b*² and upstanding tube-engaging lips *b*³, as best shown in Fig. 9.

The so-called assembling box for holding and spacing the radiating fins *b* is made up of a lower or bottom plate 24 and an upper or top plate 25. The bottom plate 24 is provided with parallel transverse slits 26 that receive the lower portions of the properly assembled radiator fins *b*, and the upper plate 25, in its under side, is formed with similar transverse slits 27 that receive the upper portions of said fins. The webs formed on the upper portion of the bottom plate 24 by the slits 26 are provided with approximately V-shaped transversely spaced notches 28 that receive the laterally bent lips *b*³ of the assembled radiator fins and hold the tube passages *b*² in alignment for the insertion therethrough of the triangular tubes *a*. The webs formed in the upper side of the top plate 25 are likewise formed with angular notches 29 that engage the upper portion of the upper row of lips *b*³ and further assist in holding the radiator fins *b* with their tube passages *b*² properly aligned. To firmly but detachably hold the two plates 24 and 25 clamped onto the assembled radiator fins, I preferably employ approximately U-shaped clamps 30, the prongs of which flare slightly so that when forced to position onto the two plates, as best shown in Figs. 1 and 4, they firmly clamp the assembled radiator fins *b* in proper relative positions for the insertion therethrough of the triangular tubes *a*.

In the operation of this assembling machine, the tubes *a* will be placed on the plungers 22 while the latter are turned upward, as indicated by dotted lines in Fig. 1. As a convenient means for oscillating the rocker bar 21, it is shown as provided at one end with a projecting arm 31 equipped with a weight 32 which is of less weight than the plungers but will operate to gravity-hold the plungers in upturned positions when they are moved to such positions.

When the plungers equipped with the tubes are turned down to horizontal position, as shown by full lines in Figs. 1 and 2, they are aligned with the tube passages in the assembled fins *b* contained in the assembling box or frame, and they will be gravity-held in such position.

When air is introduced into the rear end of the cylinder 11, the piston 12, cross-head

and plungers will be moved forward and the tubes will be forced through the aligned tube passages of the assembled fins. Thus, by a single movement, all of the tubes of the radiator core will be properly assembled with all of the radiator fins. When air is introduced into the front end of the cylinder 11, the piston 12 will be retracted or moved rearward and the plungers 22 will be withdrawn from the tubes, leaving the tubes frictionally held in contact with the lips *b*³ of the radiator fins *b*. When the clamps 30 are removed, the top plate 25 will be released and may be lifted from position and then the complete assembled radiator core may be lifted from the lower plate. As is evident, the tubes and fins of a radiator core may be very quickly assembled. The friction between the tubes and fins will be such that the core may be readily handled as an entirety and will require no other holding or connecting means while being subjected to dipping, soldering or sweating for the purpose of forming more permanent and rigid connection between the tubes and fins.

The machine described, while especially designed for assembling of the tubes and fins of radiators such as disclosed in my prior pending application, may, nevertheless, be generally used for the assembling of tubes and fins for radiator cores and the like.

What I claim is:

1. A machine for assembling the tubes and fins of a radiator core, comprising means for spacing and holding the fins properly aligned in parallel arrangement, a group of parallel tube-spacing plungers, a support for said plungers mounted for oscillatory movement to carry said plungers into and out of alignment with the fins, and means for reciprocating the support to cause said plungers to carry the tubes through the assembled fins. 100

2. A machine for assembling the tubes and fins of a radiator core, comprising means for spacing and holding the fins properly aligned in parallel arrangement, a group of parallel tube-spacing plungers, a support for said plungers, means for moving said support to cause the plungers to carry the tubes through the assembled fins, said fin-spacing means comprising upper and lower plates having slits for spacing the fins, and means for detachably connecting said two plates. 105

3. A machine for assembling the tubes and fins of a radiator core, comprising means for spacing and holding the fins properly aligned in parallel arrangement, a group of parallel tube-spacing plungers, a support for said plungers, and means for moving said support to cause the plungers to carry the tubes through the assembled fins. 120

fins, said fin-spacing means comprising upper and lower plates having parallel slits for spacing the fins and having notches to receive and align lips formed on the fins and a sliding cross-head to which said plunger support is hinged for movements of 20 the plungers from approximately horizontal to approximately vertical positions.

5 adjacent to their tube passages.

4. The construction defined in claim 3 in further combination with U-shaped clamps detachably engageable with said upper and lower plates to clamp the same onto the 10 fins.

5. A machine for assembling the tubes and fins of a radiator core, comprising means for spacing and holding the fins properly aligned in parallel arrangement, a 15 group of parallel tube-spacing plungers, a support for said plungers, means for moving said support to cause the plungers to carry the tubes through the assembled fins,

6. In a machine for assembling the tubes and fins of radiator cores, the combination with a horizontal frame, of a fin-spacing 25 box adapted to hold the fins in assembled positions, a cross-head slideable on said frame toward and from said assembling box, a plunger-supporting bar hinged to said cross-head, and a plurality of parallel 30 plungers secured to said hinged bar and adapted when turned into horizontal position to force said tubes through the assembled fins.

In testimony whereof I affix my signature.
MEINHARD WITTE.
